F. A. ZIKA,
ELECTRIC CURRENT CONDUCTING AND DISTRIBUTING MEANS,
APPLICATION FILED JUNE 9, 1913.

1,133,524.

Patented Mar. 30, 1915.

UNITED STATES PATENT OFFICE.

FRANK A. ZIKA, OF CHICAGO, ILLINOIS, ASSIGNOR OF ONE-HALF TO JAMES E. HABBY,
OF CHICAGO, ILLINOIS.

ELECTRIC-CURRENT CONDUCTING AND DISTRIBUTING MEANS.

1,133,524.

Specification of Letters Patent. Patented Mar. 30, 1915.

Application filed June 9, 1913. Serial No. 772,526.

To all whom it may concern:

Be it known that I, FRANK A. ZIKA, a subject of Austria-Hungary, and resident of Chicago, in the county of Cook and State of Illinois, have invented certain new and useful Improvements in Electric-Current Conducting and Distributing Means, of which the following is a full, clear, and exact specification.

10 My invention relates to improvements in electric current conducting and distributing means, and has especial reference to devices of this character for conducting and distributing high potential electric current to 15 the spark plugs of an internal combustion engine.

Heretofore the common, and I may say universal practice has been to separately connect the spark plugs with the distributors of combustion engines by numerous wires, corresponding in size with the slight current to be carried by them, and which are therefore so small that they are frequently broken by the constant vibration 25 produced by the operation of the engine which also finally crystallizes the copper of their structure thereby increasing their tendency to break, and if not, by corrosion from exposure to oil, and short circuiting by 30 water, which wires being as they are, more or less over burdened with a heavy coating of insulation, frequently break, or are short circuited by water without there being any visible exterior signs to indicate where the 35 trouble is, whether a short circuit, or a break is located, and as a result of which this numerous wire connection is entirely unreliable and unsatisfactory.

The prime object of this invention is a 40 means by which it is for the first time made possible and practical to connect the plugs with the distributor of internal combustion engines however many there may be, and in the entire absence of the use of numerous 45 wires, of delicate wires and of any wire which can possibly be subject to any of the conditions and objections above specified. Furthermore to accomplish the above object by means of a rotatable structure herein- 50 after specifically described as such, as distinguished from a fixed structure described

in another application filed contemporaneously herewith.

Another object of my invention is to provide an apparatus combining in a single device means for conducting the high potential current from a source of electric supply to the several spark plugs of the cylinders of internal engines, wherein the conductor is highly insulated; bodily supported, and thereby protected against the deleterious effects resulting from mechanical vibration; which is capable of distributing the current for the ignition sparks in proper time relation with the movement of the respective pistons of the engine; and which furthermore, is capable of adjustment to advance or retard the spark-time effect with reference to said piston movements.

Another object of my invention is to provide means for energizing the apparatus from either of one or more independent sources of current supply.

Other and further objects of my invention will become readily apparent to persons skilled in the art from a consideration of the following description when taken in conjunction with the drawings wherein:—

Figure 1 is a side elevation of engine of an automobile showing my improved device supplied hereto. Fig. 2 is an enlarged, longitudinal, central section taken on line 2—2 of Fig. 1. Fig. 3 is a transverse section taken on line 3—3 of Fig. 1. Fig. 4 is a detail section taken on line 4—4 of Fig. 3. Fig. 5 is a casing containing an induction coil and a switch, operable to switch the secondary of the induction coil to a live element of the distributor and to simultaneously close the primary circuit of said induction coil, and to open said circuit when the magneto is adapted to be put into electrical communication with said conductor and to close said magneto circuit for this purpose.

I have shown my improved conductor and distributor in association with an engine adapted to propel an automobile and in this particular exemplification 10 represents the side frame of an automobile, 11 a four cylinder engine; 12 a high potential, double circuit magneto and 13, means for driving the

inductor of the magneto from the shaft of the engine.

14, 15, 16 and 17 are the spark plugs of the respective cylinders of the engine.

5 18 is the stem, or tube, for supporting the vehicle steering wheel and containing a shaft that communicates with the running gear of the vehicle.

19 is a shaft adapted for movement to 10 vary the spark lead, arranged for proper communication with the distributor. In this specific instance, 20 is a crank arm adapted for communication with my distributing apparatus by means of links and shafts to be 15 hereinafter more fully described.

Specifically 21 is a brass tube, or jacket, loosely held in brackets 22 and 23 at the respective ends thereof. Each bracket consists of a strap 24 that surrounds the tube 21 20 and is secured to a cleat 25, fixed to the engine head 11' and secured to the said bracket by means of bolts 26. The arrangement is such that the diameter of the band 24 may be readily adjusted so as to permit the jacket 25 21 to turn freely therein and yet with some frictional resistance so that it may remain in place to which it has been rotatably moved.

An inner, rotatable member 25 consists 30 of a metal tube 26 that projects somewhat beyond the outer jacket 21 at each end, as at 27 and 28. The tube 26 is mounted upon a shaft 29 that is insulated therefrom by means of a hard rubber tube 30. The shaft 35 29 extends part-way through the tube 30 at one end and projects therefrom at the other end into a bearing 31, that is located within the magneto 12, and carries on its outer end a gear wheel 32, that is in mesh with a 40 pinion 33 secured on the shaft of the inductor of the magneto. Power is communicated to the wheel 32 by means of a pair of bevelled gears 34 and 35. The wheel 32 is rotated at the proper speed relation with 45 reference to the pistons within the cylinders of the engine 11. Any means, other than that shown, may be employed for rotating the shaft 29, in order that it may preserve the proper synchronism with the reciprocating 50 pistons.

The metal conducting tube 26, of my distributor, is surrounded by a rubber tube 36, and by this means the conductor 26 is highly insulated both inside and outside, and is 55 well adapted to carry the high potential current for which it is intended.

The rotating member 25, carries on the tube 36, a ball bearing member 37, near each end and, preferably, under the brackets or 60 supports 22 and 23, respectively. A corresponding ball bearing member, or ring 38, is carried by the outer jacket, or metal tube 21, so that by this means the rotating member 25 may be freely and readily rotated 65 within its protecting jacket support.

Located at intervals of 90 degrees around the axis of the rotating member 25, for a four cylinder engine, are conducting plugs or buttons 40, 41, 42, 43, of which there are four, one corresponding to each of the respective cylinders and which are, preferably, flush with the outer surface of the rotating member 25. These buttons pass the tube 36 and are brought into electrical contact with the rotating tube 26, located 70 in a vertical plane, and secured to the outer tube, or jacket 21, are four stems or conductors 45, 46, 47, and 48 that have electrical association with the contact pieces or buttons 41, 42, 43, and 44, respectively. 80

In the specific illustration the parts 45-47 are shown to carry spring pressed shoes 50, which normally bear upon the outer surface of the rotating member 25. It is not essential that the shoes 50 should make actual metallic contact with the buttons 41-44 of the rotating member, as its close proximity is all that is necessary, in order that the sparks shall pass from the rotating conductor to the relatively stationary shoes 50. The shoes, 50, and conductors 45-48 are secured to the casing 21 by screw plugs 52 which carry insulating thimbles 53. By this means the relatively fixed conducting parts are entirely and completely insulated from the casing 21. 95

Telescoping conductors, capable of linear adjustment, carry the current from the stems 45-48 to the conducting portions of the respective spark plugs 16. They each 100 consist of an inner member 54, pivoted to a contacting member 55, as at 56, and an overlying tubular member 57, pivoted to the stems 45-48 as at 58. This outer metallic tube is covered by an insulating tube 59, 105 composed preferably of hard rubber, or the like. By this means the distance between the spark plug 16 and the respective stem may be varied, as when the jacket 21 is oscillated. A screw cap 60, surrounds the 110 stem 61 of the spark plug 16 and holds the conducting member in place.

From the foregoing description it will be apparent that if the inner tubular conductor 26 be charged by a high potential current 115 that, the current will be conveyed to the respective spark plug, when the buttons 41-44 come into conjunction with the respective shoe 50, and it will be further manifest that the distance between the stem 45-48 and the spark plug 16, when varied will be compensated for by the telescopic arrangement of the conductors 54 and 57. 120

The current from the magneto 12 may be conveyed to the rotatable conductor 26 by 125 means of the lever 62 that is pivoted as at 63 to a portion of the magneto. When the end of the said lever is brought into contact with the projecting end 28, of the rotating member 26. A reciprocatable rod 65 is sup- 130

ported in bearings 66, 67, and 68 that are secured to the head 11' of the engine 11, the outer end of the rod being connected to the lever 62, by means of a link 69, made preferably of insulating material, so that when the rod 65 is pushed toward the magneto the link 69 will press the lever 62 into contact with the conducting portion 28 of the rotating member 26 and thereby convey the 10 current generated by the magneto to the said rotating member. When a magneto only, is used for supplying current for this purpose, the connection just described is sufficient, but if two sources of electrical energy are to 15 be alternatively utilized for the same set of spark plugs, it may be done conveniently in the manner now to be described.

70 is a battery, adapted to energize an induction coil 71, that is located in a casing 72. The positive end of the battery is conducted by wire 73 to binding post 74 and the negative end is connected by wire 75 to binding post 76. Inside of the casing 72, is a vibratable, hand operated bifurcated lever 25 77, pivoted as at 78, and carrying a conductor 79, on one of its ends, and a conductor 80 on its other end. A corresponding lever 81, is shown in Fig. 1, located on the outside of the casing 72, whereby the lever 30 77 located within the casing may be coincidentally moved when the handle 82, of the lever 81 is grasped by the hand of the operator. On the lower extended end of the lever 81, is connected a link 84, pivoted there- 35 to, as at 85, and to the reciprocatable rod 65, as at 86. This link is composed, preferably, of insulating material, such as hard rubber, so as not to "ground" any portion of the conducting devices that are contained 40 within the casing 72. One of the primary terminals 87 of the induction coil 71, is connected to the binding post 74, the other similar terminal, 88 is connected to the binding post 76 through part 80 and contacts 96 and 45 97 thereby completing the primary circuit of the induction coil.

The rotating member 26 is connected to the terminal 89, of the casing 71, by wire 90 and this terminal is connected on the inside 50 of the casing with a secondary terminal of the induction coil by a wire 91. The other terminal of the secondary circuit, of the induction coil 71, is connected to a contact 93, adapted for connection with the movable 55 switch part 79. The companion contact, 94, is connected by any convenient means, to any portion of the frame of the engine, or in other words it is "grounded."

When the outside handle 81 is moved to 60 the left, immediately over the button 95, the switch part 80, makes electrical connection with the contacts 96 and 97, these contacts being connected with the binding post 76, by a wire 98, and by the wire 88 to the primary terminals of the induction coil, re-

spectively. Now when the handle 82, of the lever 81, is grasped, and the lever is pulled over to the left, until it is immediately over the button 95, the rod 65 is thereby reciprocated and the connections within the casing 70 72 are completed in the manner heretofore described and at the same time the pivoted lever 62, is removed from contact with the connecting part 28, of the rotating, conducting member 26, so that the rotating member 75 26 is now energized, by the instrumentality of the battery 73, and its coacting induction coil 71, in a manner well understood by persons skilled in the art.

In order that the spark-time relation may 80 be varied, the jacket 21 is capable of oscillation upon its bearings 22 and 23, so that the association between the conducting shoes 50 of the respective parts 45-48 may be made sooner or later with regard to the conducting buttons 41-44 which are parts of the rotating member, and to this end I provide a projecting arm 100, on one side of the casing, connected by a link 101, pivoted thereto, as at 102, and also pivoted, as at 103, 90 to a crank arm 104. This latter arm is rotatively secured to a shaft 105 which is supported in the brackets 66 and 67. On the outer end of the shaft 103 is a crank arm, 106 connected to the crank arm 20 by means 95 of a link 107, so that when the shaft 19 is oscillated, through this connecting mechanism, the shaft 105, is oscillated and the jacket 21 is correspondingly oscillated, so as to move the contact shoes 50 to the right, or to the left, as desired, with reference to the respective rotatable contacts 41-44 carried by the rotatable member 26, thereby to change the time relation of the spark with reference to the respective reciprocating pistons of the internal combustion engine. It is of course manifest that either the battery or the magneto may be used independently of the other, and alternatively, as desired, in connection with my current conducting, 105 and distributing device.

In ordinary practice each of the spark plugs are separately connected to the distributor, located at a remote point from the plugs, by means of a delicate conducting wire, overburdened with heavy coatings of insulation, and as the current, to be carried by these conductors, is slight the wires are correspondingly small and are not sufficient to withstand the constant vibration which 115 results from the operation of the engine and which finally produces crystallization in the copper conducting structure causing such conductors to be easily broken and ultimately destroyed. This effect frequently takes place within the body of the insulation without visible exterior signs to indicate the trouble rendering such method of conducting the current to the plugs entirely 120 unreliable and unsatisfactory.

4
My device is bodily supported so as to be unaffected by the vibration produced by the engine and it is so arranged that the conductor thereof is protected by the highest quality of insulation.

5 While I have herein shown and described a single embodiment of my invention for the purpose of clear disclosure it is to be understood that my invention is not to be 10 limited to the single exemplification further than defined by the appended claims.

Having described my invention, what I claim is:

1. A device of the character described, for 15 cooperative association with an engine having a plurality of cylinders and corresponding spark plugs, comprising a cylindrical jacket; an elongated, insulated, rotatable hollow conductor, projecting through said jacket at both ends and rotatably supported 20 in said jacket; contact buttons projecting laterally through said insulation at intervals along said conductor and connected thereto; means for making electric connection 25 with said conductor at either projecting end; relatively stationary conductors for connection respectively to said spark plugs adapted for electric coöperation in relative order with said rotatable buttons 30 and means for electrically energizing said rotatable conductor.

2. A device of the character described, for 35 cooperative association with an engine having a plurality of cylinders and corresponding spark plugs, comprising an elongated, insulated rotatable hollow conductor, adapted for rotatable support on said engine; contact buttons projecting through said insulation at intervals along and connected 40 to said conductor; a jacket inclosing said conductor through which said conductor passes and from which it projects; relatively stationary conductors supported on said jacket for connection, respectively; to said spark 45 plugs adapted for electric coöperation, in relative order, with said rotatable buttons, and a shaft extending into said hollow conductor and projecting from said jacket to afford means for rotating said conductor.

50 3. A device of the character described, for coöperation with an internal combustion engine having a spark plug, comprising a protecting jacket; straps for securing it to an engine, one at each end; an elongated, insulated electric conductor rotatable in said jacket and projecting at each end therefrom; ball bearing members within said jacket, upon which said conductor is rotatable; electric connections adapted for connection to each end of the projecting structure; a conducting button projecting from one side and connected to said conductor; a 55 yieldable button projecting into said jacket and supported thereon for electrical coöperation with said conducting button and

means for connecting said yieldable button to said spark plug.

4. In a device of the character described, in combination with an internal combustion engine having a plurality of spark plugs, 70 of an insulated, rotatable conductor; a conducting button projecting from one side thereof and connected thereto; a relatively stationary, protecting jacket surrounding said rotatable conductor and supported on 75 said engine; a coöperating conducting terminal, in substantially the same radial plane as said button, supported on said jacket; means for rotating said conductor; means for energizing said rotatable conductor and 80 means for oscillating said jacket to change the time of coincidence of said rotatable button and said conducting terminal.

5. In a device of the character described, 85 in combination with an internal combustion engine having a plurality of spark plugs, of an insulated, rotatable conductor; conducting buttons projecting from the sides thereof and connected thereto; a relatively stationary protecting jacket surrounding 90 said rotatable conductor and supported on said engine; coöperating conducting terminals in substantially the same radial plane as the respective buttons, supported on said jacket, there being one said button 95 and one said terminal for each of said spark plugs; means for rotating said conductor; two sources of electric current for energizing said conductor; means for oscillating said jacket to change the time of coincidence 100 of said rotatable button and said conducting terminal and means for alternatively connecting either source of electric current in circuit with said rotatable conductor.

6. In a device of the character described, 105 in combination with an internal combustion engine having a plurality of spark plugs, of an insulated rotatable conductor; a corresponding number of conducting buttons projecting therefrom, one for each spark 110 plug; a protecting jacket, surrounding said conductor; a plurality of co-acting, conducting terminals, in substantially the same longitudinal plane, one for each spark plug, supported on said jacket; means for oscillating said jacket to change the time of coincidence 115 of said buttons and respective terminals; and means at each end of said rotatable conductor whereby to connect it 120 in an electric circuit.

7. In a device of the character described, 125 in combination with an internal combustion engine having a plurality of spark plugs, of an insulated conductor provided with bearings for rotation in a surrounding protecting jacket; a plurality of conducting buttons projecting therefrom and suitably disposed, one for each spark plug; a protecting jacket surrounding said conductor, provided with bearings therefor; a plu- 130

rality of co-acting conducting terminals, in substantially the same longitudinal plane, one for each spark plug, supported on said jacket, means for oscillating said jacket to change the time of coincidence of said buttons and respective terminals; and means to rotate said rotatable conductor in cyclic relation with the power shaft of said engine.

In witness whereof, I have hereunto set my hand and affixed my seal, this 7th day 10 of June, A. D. 1913.
